UNITED STATES PATENT OFFICE

ALLAN S. BARROWS, OF LOS ANGELES, CALIFORNIA, ASSIGNOR TO THE YOUNGSTOWN STEEL DOOR COMPANY, OF CLEVELAND, OHIO, A CORPORATION OF OHIO

METALLIC CAR DOOR

Application filed March 20, 1926. Serial No. 96,166.

This invention relates to improvements in metallic car doors.

An object of the invention is to provide an all metal door, especially adapted for side doors of railway cars, although its application is not necessarily limited thereto, and in which there is employed a minimum amount of material consistent with the necessary strength, which material is concentrated at those points where the greatest stresses and strains are imposed. The invention also contemplates such a metal door composed mainly of sheet metal, reinforced along the edges thereof and inwardly of said edges.

Another and more specific object of the invention is to provide a metal door of the character indicated made up of a plurality of metallic panels provided with fabricated reinforcements of a novel character, which may include offset portions such as corrugations or the like formed in the sheet metal of which the door is composed and extending to one side of the main plane of the door in conjunction with reinforcing rolled sections of various angular formations disposed at the inner face of said door and extending into said offset portions for bracing the same and the door structure generally, additional means being provided on the under face of said door in position to extend over the reinforcing elements and the mouths of the offsets so as to provide a hollow tubular formation in which the reinforcing element in each case operates as a brace or strut for the sheet metal forming the corrugation as well as for the door generally, the reinforcing elements being concealed from view, protected from the weather, and removed from the front face of the door, whereby the front face of the door is smooth and free of obstructions which occur in ordinary sheetmetal doors, which collect moisture and other foreign matter, resulting in rapid deterioration and loss in efficiency.

Another object of the invention is to provide an edge construction at the rear portion of the door, wherein a rolled section is secured to the main body portion and is provided with an inwardly turned extension disposed to operate as a spark seal.

Other and further objects of the invention will more clearly appear from the description and claims hereinafter following.

In the drawings forming a part of this specification, Figure 1 is a front elevational view of a car door made up in accordance with my invention. Figure 2 is a vertical, sectional view of the door on the line 2—2 of Figure 1. Figure 3 is a horizontal, sectional view of the door construction on the line 3—3 of Figure 1. Figure 4 is a fragmentary, horizontal section of the rear part of a door showing a somewhat different embodiment of the invention. Figure 5 is a fragmentary, vertical section showing the bottom construction of the arrangement illustrated in Figure 4. Figure 6 is a horizontal, fragmentary sectional view of the rear part of a door showing another slightly different embodiment of the invention. Figure 7 is a fragmentary, vertical section of the bottom part of the door illustrated in Figure 6. Figure 8 is a fragmentary, horizontal, sectional view of the rear part of a door showing still another slightly different embodiment of the invention. Figure 9 is a fragmentary, horizontal, sectional view of the rear part of a door showing still another embodiment of the invention. Figure 10 is a fragmentary, horizontal, sectional view of the rear part of a door showing still another embodiment of the invention. Figure 11 is a fragmentary, horizontal sectional view of the rear part of a door showing still another embodiment of the invention. Figure 12 is a fragmentary, horizontal sectional view of the rear part of a door showing still another modification of the invention. Figure 13 is a fragmentary vertical sectional view of the bottom part of a door of the character illustrated in Figure 12. Figure 14 is a fragmentary, horizontal sectional view of the rear part of a door showing still another embodiment of the invention. Figure 15 is a fragmentary, vertical sectional view of the bottom part of a door of the character illustrated in Figure 14. Figure 16 is a fragmentary, horizontal sectional view of the rear part of a door showing still another modification of the invention. Figure 17 is a fragmentary, horizontal sectional view of the rear part of a door showing still another embodiment of the invention.

zontal sectional view of the rear part of a door showing still another modification of the invention. Figure 18 is a horizontal sectional view of the rear part of a door showing still another embodiment of the invention. Figures 19 and 20 are fragmentary, horizontal sectional views of the rear parts of doors showing still other embodiments of the invention. And Figures 21 and 22 are fragmentary, vertical sectional views of different embodiments of reinforced connections between the horizontal meeting edges of the door panels.

Referring first to Figures 1 to 3 inclusive, the invention contemplates the provision of a metallic door of the usual rectangular form, and which comprises a main body portion made up of a plurality of metallic panels 10, 11, and 12, said panels having their adjacent horizontal edges overlapped and rigidly connected by welding or by rivets as indicated at 13. Each of the panels is made of relatively thin sheet metal, and in order to reduce this thickness to a minimum consistent with the necessary strength, each panel is provided with strengthening indentations, embossments, or corrugations, in this instance being shown as horizontally disposed corrugations, indicated at 14, though in certain instances in conjunction with the reinforced edge construction of the door, as hereinafter described, it might be desirable to employ other means of bracing the portions of the panels inwardly of the edge construction by various expedients known in the art.

In providing a reinforced edge construction for the main body portion of the door comprising the fabricated panels 10, 11 and 12, the main body portion is provided with a vertical corrugation 15 adjacent its rear edge, the inwardly disposed wall 16 of the corrugation 15 being of somewhat greater extent than the outwardly disposed wall 17 of said corrugation, the main body portion outwardly of the corrugation 15 extending outwardly of the corrugation to provide a marginal section 18, which by reason of the less extent of the wall 17 of the corrugation is offset outwardly somewhat from the main plane of the door to permit efficient application of reinforcing elements hereinafter described. The forward edge of the door is also provided with a vertically disposed corrugation 19, similar to the corrugation 15 having a wall 20 of greater extent than the wall 21, the main body portion of the door outwardly of the corrugation having a marginal section 22 offset in the same manner as the marginal section 18. Adjacent the top edge of the door the uppermost horizontal corrugation 23 is formed in the same manner as the corrugations 15 and 19, having a wall 24 of greater extent than the wall 25, the main body portion of the door extending outwardly of the corrugation 23 to provide the marginal sec-

tion 26, which by reason of the less extent of the outer wall 25 is offset in the same manner as the marginal portions 18 and 22. The lowermost horizontal corrugation 27 is formed in the same manner as the front, rear and top corrugations, having an inner wall 28 of greater extent than the outer wall 29, the main sheet outwardly of the corrugation being provided with a marginal section 30 offset in the same manner as marginal sections heretofore referred to. It will be noted, as shown, that the vertical corrugations 15 and 19, merge at their ends with the ends of the uppermost and lowermost corrugations 23 and 27, and the horizontal corrugations between the uppermost and lowermost corrugations preferably merge at their ends with the vertical corrugations 15 and 19.

Means are provided for reinforcing the edge portions of the main body portion, and at the rear of the door, said means take the form of an angular rolled section 31 having an angularly extending portion or flange 32 which is disposed substantially at right angles to the main plane of the door and extends into the corrugation, terminating at its outer end in a bulb formation 33, which abuts the inner bottom wall of the corrugation 15, said member having at its opposite end an angularly turned portion 34^a extending outwardly toward the outer edge of the marginal section 18 and lying flat-wise thereagainst. In this connection, it should be noted that the less extent of the wall 17 of the corrugation offsets the marginal section 18 to such an extent that the angular portion 34^a is disposed in a plane substantially common with the main plane of the main body portion of the door. It will be noted that the angular portion 32 of the angular member 31 acts as a brace or strut for the edge of the door and for the corrugation. In conjunction with the rolled reinforcing section 31, a reinforcing strip 34 is utilized. The strip 34 has its inner edge portion connected to the main body portion of the door by welding or rivets as indicated at 35, said strip bridging the corrugation and extending outwardly thereof so as to rest against the angular portion 34 of the section 31, as shown, the marginal portion 18, the angular portion 34 and the outer edge portion of the strip 34 being rigidly secured together by welding or rivets as indicated at 36. In the case of the rear edge of the door, I provide a spark strip which, in this instance, is in the form of an angle bar 37, having one flange 38 lying against the marginal section 18 and secured in position by the rivets 36, the remaining angular portion 39 of the angle bar 37 extending inwardly a suitable distance beyond the main plane of the door, and so disposed as to co-operate with means ordinarily provided on car door frames so as to act as a spark strip.

The forward edge of the door is provided

with an angular section 39 similar to the section 31 arranged with respect to the corrugation 19 and marginal portion 22 in identically the same manner as described for the rear construction, a reinforcing strip 40 also being secured to the door and arranged with respect to the angular member 39 and the corrugation in identically the same manner described with reference to the rear edge construction. The upper edge of the door is also provided with an angular reinforcing section 41 arranged with respect to the corrugation 23 and marginal section 26 in the identical manner described with reference to the front and rear edges of the door, a reinforcing strip 42 also being provided and arranged in a manner identically similar to that described with reference to the front and rear edges of the door. The bottom construction of the door also includes an angular rolled section 43 arranged with respect to the corrugation 27 in identically the same manner as described with reference to the other edges of the door, a reinforcing strip 44 being provided and arranged in the same manner as the reinforcing strips associated with the other edges of the door.

Referring to Figures 4 and 5 of the drawing, fragmentary views only are shown of the rear and bottom edges of the door, but it will be understood that the edge constructions described in connection with Figures 4 and 5 may be applied to the top, bottom, front and rear edges of the door, in the same manner described in connection with Figures 1 to 3, inclusive, it being deemed unnecessary in connection with Figures 4 and 5, and with the other modifications hereinafter described, to illustrate a complete door, since it will be appreciated that the main body portion of the door may be similar to that shown in Figures 1 to 3, and that the bottom edge construction shown in Figure 5 is duplicated on the forward and top edges of the door, while the rear edge of the door is of a slightly different formation by reason of the provision of the spark seal. Referring to the rear edge construction illustrated in Figure 4, a vertical corrugation 50 is provided having an inner wall 51 of greater extent than the outer wall 52, so as to offset the marginal portion 53 in a manner heretofore referred to. Associated with the corrugation 50 is an angle member having one angle portion 54 extending into the corrugation, the outer end of said angular portion abutting the bottom wall of the corrugation, the inner end of the angular member 54 being provided with an angular portion 55 extending outwardly toward the rear edge of the door, said angular portion in this instance, being provided with an integral inwardly turned angular section 66 extending inwardly of the main plane of the door and disposed to operate as a spark strip. A reinforcing strip 57 is provided, the edge por-

tions inwardly of the corrugation being secured to the main body portion of the door by welding or rivets as indicated at 58, said strip bridging the corrugation and lying flat against the angular portion 55 of the reinforcing section, the marginal portion 53, the angular section 55 and the outer edge portion of the strip 57 being secured together by welding or riveting as indicated at 59.

The bottom construction of the door illustrated in Figure 5, includes a corrugation 60 similar to the corrugation 50, and a reinforcing strip 61 and an angular member 62, which is identical with the angular member described in connection with Figure 4 except that the angularly turned section 56, forming the spark strip, is, of course, omitted. The construction at the top and front edges of the door will be similar to that shown in Figure 5.

Referring to Figures 6 and 7, the construction shown herein is identically the same as that shown in Figures 4 and 5, the corrugation 70, and the strip 71 being identical to the corrugation 50 and strip 57. In this construction, the reinforcing section is in the form of an angular member having an angular portion 72 extending into the corrugation and having another portion 73 extending at right angles thereto the inner angular portions abutting the metal forming the corrugation. At the opposite end of the angular portion 72 the angular member has an angular section 73^a terminating in an inwardly extending angular part 75 forming a spark seal, the parts being secured together in the same manner disclosed in Figures 4 and 5. Figure 7 discloses the identical arrangement disclosed in Figure 6 except that the angularly turned part 75 on the angular member 74 is omitted, and in this connection, the same reference characters used to designate the parts in Figure 6, designate similar parts in Figure 7.

Referring to Figure 8, the corrugation 80, and the marginal section 81 are similar to the corrugations 50 and marginal section 53. In this construction, an angular member 82 is provided, one flange 83 of which extends substantially normally to the main plane and the main body portion, and the other flange 84 extends substantially at right angles thereto outwardly toward the rear edge of the door. In this construction a reinforcing strip 85 is provided which has its inner edge portions secured to the main body portion of the door by welding or rivets as indicated at 86, said strip extending across a portion of the corrugation and lying against the portion 84 of the angular member 82, being secured to said angular portion as indicated at 87, the extremity of said strip 85 being curled over the angular portion 84 and marginal section 81 as indicated at 88, the curled portion, the marginal section 81 and

the angular portion 84 being rigidly secured together by rivets 89 or other suitable securing means. It should be understood that a reinforcing edge construction of this character may be utilized in connection with any one of the four edges of the door, or with all of said edges.

Referring to Figure 9, there is shown a construction which is identical with the construction shown in Figures 1 to 3 with the exception that instead of the separate angle member 37 forming the spark strip, the angular portion corresponding to the portion 34 of the bulb angle is provided with an integral 10 inturned angular section 90, extending inwardly of the main plane of the door to provide a spark seal. The remaining portions of the edge construction comprise the bulb angle member 91, the corrugation 92, and 15 the reinforcing strip 93, which parts correspond to the bulb angle 31, the corrugation 15, and the reinforcing strip 34, respectively, as shown in Figures 1 to 3 and the parts are arranged in an identically similar manner 20 but for the exception above noted. In connection with this figure, it will be appreciated that the top, front and bottom of the door may have one or more of its edges formed of a construction identical with the rear construction described except for the omission 25 of the angular part 90 forming the spark seal.

Referring to Figure 10, the main body portion 100 is provided with a vertical corrugation 101, and a marginal portion 102, an angular member 103 being provided, which has an angular portion 104 extending into the corrugation and having its outer end abutting the inner wall of the metal of which 30 the corrugation is formed, the angular member 103 being provided with right angular flanges 105 and 106, the flange 105 being secured to the main body portion 100 by means of welding or rivets 107 and the flange 106 being secured to the marginal portion 102 by welding or rivets as indicated at 108. In connection with this construction, the angular portion provides means spanning the corrugation, and includes an integral flange which 45 extends into the corrugation to brace the same. The edge construction disclosed in this embodiment of the invention may be applied to one or all edges of the door as desired.

Referring to Figure 11, the main body sheet is indicated at 110, said body sheet being provided with a vertically disposed corrugation 11, the peak or crest 112 of which is flattened as shown, the construction including 50 a marginal section 113 outwardly of the corrugation. Disposed within the corrugation is an angle bar 114, one flange 115 of which fits within the corrugation and rests against the flattened portion 112 of the inner wall thereof, the flange 116 extending in-

wardly toward the main plane of the door. The angle member 114 is preferably secured in the corrugation by means of welding or rivets as indicated at 117, which connect the flange 115 and the crest of the corrugation. In connection with this arrangement, it will be appreciated that the same may be utilized in connection with one or all edges of a door in the manner heretofore referred to.

In the construction shown in Figures 12 and 13, the main body portion is denoted by the reference character 120, said main body portion being provided with a corrugation 121, said corrugation at its crest being provided with an integral hollow rib or smaller corrugation 122, the outer wall portion 123 of the corrugation being of less length than the other wall, and terminating in a marginal section 124. Disposed within the corrugation 121 is an angular reinforcing member 125 including an angular portion 126 extending substantially normal to the main plane of the door, having at one edge an angularly turned portion 127 which abuts the inner wall of the metal of which the corrugation 121 is formed, and the angular member 125 is provided with an angular section 128 at its inner end, the outer extremity of which is provided with a turned part 129, extending inwardly of the inner plane of the door to provide a spark seal. A reinforcing strip 130 is secured to the main body portion 120 by welding or rivets as indicated at 131, said strip extending across the corrugation and having its outer end portion 131 secured to the angular portion 128 of the member 125, and to the marginal section 124, by means of welding or rivets as indicated at 132. Figure 13 shows the edge construction as it would appear when applied to an edge of the door other than the rear edge, in this construction, the angular part 129 which forms the spark strip being omitted; consequently, similar reference characters will be utilized to designate similar parts in Figures 12 and 13.

Referring to Figures 14 and 15, 140 represents the main body portion of the door, provided with a vertical corrugation 141 at the rear edge of the door, which corrugation has a flattened crest 142, the outer wall 143 of the corrugation being of somewhat less extent than the inner wall thereof, a marginal section 144 being provided outwardly of the corrugation. In this construction, an angular member 145 is utilized, which is substantially identical in formation with the member 125 disclosed in connection with Figures 12 and 13, together with a reinforcing strip 146 similar to the strip 130 in Figures 12 and 13, the only difference in the construction disclosed in Figures 14 and 15 and Figures 12 and 13, residing in providing a somewhat different form of corrugation. It will be noted in this construction that the flange 147 fits against the flattened crest of the corrugation 142.

141, and that the angular member 145 is provided with an inwardly turned spark strip 148. The construction shown in Figure 15 is identical with that disclosed in Figure 14 except for the omission of the inwardly turned spark strip 148, and it will be appreciated that the edge construction disclosed in these figures may be used in connection with one or all edges of the door.

10 In the construction shown in Figure 16, the main body portion of the door preferably is flat at its edge. In this construction, a separate strip of metal 151 is provided, which is secured to the sheet forming part of the main body portion of the door, and said separate strip of metal 151 has formed therein a corrugation 152, the inner wall 153 of said corrugation being of somewhat greater extent than the outer wall 154, the portion of the strip outwardly of the corrugation providing a marginal portion 155. Disposed within the corrugation is one angular portion 156 of a reinforcing element, the angular portion 156 having its inner end abutting the inner wall 153 of the metal of which the corrugation is formed, extending toward the main plane of the door substantially at right angles thereto. The reinforcing member is also provided with an angular portion 157 extending 20 toward the outer edge of the door, said portion lying against the marginal portion 155. An additional reinforcing angular member, preferably in the form of a Z-bar 158 has one flange, 159, overhanging the crest of the corrugation 151, the web of the Z-bar extending substantially parallel to the angular portion 156 of the angular member, the remaining flange 160 of the Z-bar lying against the outer face of the marginal portion 155 of the strip 153 in which the corrugation is formed, the flange 160, the marginal portion 155, the angular part 157, and the main body portion 150 being secured together by welding or rivets as indicated at 161, the inner edge of the strip 153 being secured to the main body portion 150 by welding or rivets as indicated at 162. In the construction just described, it will be appreciated that the strip in which the corrugation is formed provides one ply of 30 material in the edge construction, and the main body portion, 150, provides another ply of material, the corrugation being formed in one ply of material, and the angular reinforcing member being disposed in the corrugation between the plies of material and being secured outwardly of the corrugation between said plies of material. In connection with this construction, it will be appreciated that the same may be utilized in connection 40 with one or all of the edges of the door.

Referring to Figure 17, 170 represents a flat body portion of sheet metal, 171 represents a strip of material extending along the edge of the door, in which is formed a corrugation 172, the outer wall 173 of said corrugation being of less extent than the inner wall, and the portion of the strip outwardly of the corrugation providing a marginal section 174. Disposed within the corrugation is an angular member 175, having an angular portion 176 extending substantially normal to the main plane of the door, and having an angular flange 177 abutting the inner wall of the metal forming the corrugation, and also provided with an angular portion 178 lying 50 against the marginal section 174, the marginal section 174, the angular portion 178 and the outer end of the main body portion being secured together by welding or rivets as indicated at 179. The inner edge portion of the strip 171 is secured to the main body portion by welding or rivets as indicated at 180. In this construction, it will be appreciated that two plies of material are provided, one of which has a corrugation formed therein, in 60 conjunction with an angular member, rigidly secured between the plies of material and having angular portions projecting into the corrugation. The construction disclosed in connection with this figure may be applied 70 to one or all of the edges of the door as will be appreciated.

Figure 18 shows a construction in which the main body portion is designated by the reference character 190, a strip 191 being 80 provided, which strip has formed therein a corrugation, in conjunction with an angular member 192, the parts mentioned in connection with this construction being identical with the parts 150, 151 and 157, as disclosed 90 in Figure 16, the only difference in this construction from that disclosed in Figure 16 residing in the omission of the Z-bar 158. It will be appreciated that the construction disclosed in Figure 18 may be used in connection 100 with one or all of the edges of the door as desired.

Figure 19 shows a construction in which the main flat body portion is designated by a reference character 200, said body portion having formed therein a corrugation 201, the material of the body portion inwardly of the corrugation being offset as indicated at 202, and the material outwardly of the corrugation being extended to provide a marginal section 203, which lies in a plane common 110 with the offset portion 202. A reinforcing strip 204 is provided which spans the corrugation, and the inner edge portion of said strip being of a character to fit within, and lying flatwise against the inner surface of the offset portion 202, while the outer edge of the strip lies flat against the marginal section 203, the strip being connected to the body sheet by rivets 205, which are countersunk on 120 the inner side of the strip 204. By this arrangement, it will be appreciated that the inner surface of the strip 204 lies in the same plane as the inner surface of the main body portion.

In Figure 20 the main flat body sheet is indicated at 210, said sheet being provided with an offset 211, and a corrugation 212, the outer leg 213 of said corrugation being of less extent than the other leg of said corrugation, the shorter leg 213 being provided with a marginal section 214 outwardly of the corrugation. Extending into the corrugation is an angular reinforcing section 215, one flange of which extends normal to the plane of the main body sheet and the other flange of which is disposed outwardly and rests against the inner surface of the marginal section 214. A reinforcing strip 216 is provided which spans the corrugation, and has its inner end disposed in the offset 211, and the outer end resting against the under surface of the outwardly turned angular portion of the member 215, the strip being riveted to the main body sheet by rivets as indicated at 217 and the marginal section, the outturned angular portion of the section 215, and the strip 214 being secured together by rivets as indicated at 218. By this arrangement, it will be noted that the strip is disposed in a plane common with the plane of the main body sheet.

Figure 21 shows a modified form of the connecting means between the meeting edges of the panels forming the main body portion of the door. In said figure the panel is shown as being flat and is indicated by the numeral 220, said panel being provided along its lower edge with an offset 221 similar to the offsets disclosed in Figures 19 and 20, except that the same is deeper, the panel outwardly of the offset 221 being provided with a corrugation 222, and outwardly of said corrugation the panel is further provided with a marginal section 223. Disposed so as to project within the corrugation is an angular member 224, one flange of said angular member being disposed substantially at right angles to the main plane of the door, and the remaining flange disposed within the offset 221. The adjacent panel with which the panel 220 is connected is indicated by the reference character 225, said panel extending across the corrugation and having its end lying against the vertically disposed angular portion of the angular member within the offset 221, the metal forming the offset, the angular portion of the member 224, and the end of the panel 225 being connected by rivets as indicated at 226, and the marginal section 223 of the panel 220 being connected to the panel 225 by rivets as indicated at 227. In this construction the offset is deeper to provide room for additional plies of material, and in this way affords a strong, efficient connection between horizontal meeting edges of the panels forming the main body portion of the door.

The construction shown in Figure 22 comprises panels 230 and 231^a forming part of

the main body portion of the door, only so much of said panels being illustrated as to disclose the reinforced connection between the meeting edges of said panels. In this construction the lower horizontal edge of the panel 230 is offset as indicated at 231, while the corresponding edge of the other panel is flat. Secured to the offset portion 231 of the panel 230 is a reinforcing piece of material 232 which has a corrugation 233 formed therein, one leg 234 of said corrugation being shorter than the other, the short leg of the corrugation being provided with a marginal section 235 adapted to lie flatwise against the offset 231, while the opposite portion of the piece of material is formed in a marginal section 236 which lies against the face of the panel 231^a. An angular member 237 is provided having one flange projecting into the corrugation 233, and another flange disposed so as to lie against the under surface of the offset 231, the panel 231^a spanning the corrugation and lying against the vertically disposed flange of the angular member 237. The piece of material 232 is secured to the panel 231^a by rivets as indicated at 238, and the end of the panel 231^a, the vertically disposed flange of the angular member, the offset 231, and the marginal section 235 of the piece of material 232 are secured together by rivets as indicated at 239. In this construction, it will be noted that the panels 230 and 231^a lie in a common plane, while the meeting edges of the panels are securely fastened together by means of a reinforced connecting structure.

In the above described arrangements, it will be appreciated that in each instance a reinforced sheet metal door is provided in which the reinforcing elements are disposed upon the inner face of the door and project into outwardly offset portions formed in the door, whereby the outer face of the door is left smooth and free of reinforcing angular members which, in the ordinary types of metal doors, collect moisture and other foreign matter, causing corrosion and rapid disintegration of the parts of which the door is composed. In addition, the reinforcing elements are concealed from view, thereby providing a door having an attractive appearance.

An important feature of the invention resides in providing a braced corrugation of the character described in which the reinforcing section has a portion extending outwardly from the main plane of the door and substantially at right angles thereto, and into abutment with the surface of the bottom wall forming the trough or valley of the corrugation, so that the corrugation cannot be injured by lateral crushing or denting which would weaken the same, as the rolled section lying immediately beneath the metal forming the corrugation and at right angles thereto operates as a backing for the corrugation

and effectively prevents such crushing or denting and additionally stiffens and braces the corrugation longitudinally and braces the door structure generally. The bracing function of the reinforcing section is augmented by the provision of the reinforcing strip which extends across the mouth of the corrugation and is fastened to the metal of the door at each side of the corrugation, thereby bracing the corrugation against spreading, and providing an abutment against which the rear edge portion of the reinforcing element bears. Attention is also called to the fact that by providing an angular reinforcing element of the character disclosed, one angular portion thereof may be clamped between the marginal section of the main body member and the reinforcing strip, and thus secured in position without the necessity of perforating the corrugation itself with consequent weakening thereof, and in this way reducing the number of corrugations which are necessary to stiffen the metal and providing a door structure of exceptional strength and durability.

Although the offsets in the sheet metal have been heretofore designated as indentations or corrugations, it will be understood that these terms are intended to cover embossments, depressions of undulations in the metal of any other character, which reinforce the metal and provide troughs or valleys for the accommodation of the reinforcing elements in the various manners heretofore referred to.

It also should be noted that any of the constructions heretofore described are capable of use upon one edge, two edges, three edges, or four edges, as desired, and it will be understood that the reinforced edge construction as described may be utilized in conjunction with reinforced corrugations within the reinforced edge construction, or may be utilized with other known means of reinforcing the body portion of the door within the reinforced edges, as by dishing or the like.

While I have herein shown and described what I now consider the preferred manner of carrying out my invention, the same is merely illustrative and I contemplate all changes and modifications that come within the scope of the claims appended hereto.

I claim:

1. A fabricated car door of metal comprising a sheet metal body portion having a strengthening corrugation or indentation extending to one side of the main plane of said door; a reinforcing element rigidly associated with said door and provided with a bracing portion disposed in said corrugation and extending at an angle to the main plane of the door toward the inner bottom wall of the trough of said corrugation and terminating in said corrugation, the metal form-

ing the inner extremity of said terminal portion being thickened.

2. A car superstructure member including: a sheet metal panel having a corrugation therein; and a strut-like, commercial section reinforcing element for and extending lengthwise of the corrugation, said element including two sections at right angles to each other, one of which extends within the corrugation in spaced relation to the portions of the corrugation which define the mouth thereof.

3. As an article of manufacture for a car, a sheet metal panel having a corrugation therein; and a strut-like reinforcing element extending lengthwise of the corrugation and having a section projecting within the corrugation and engaging with the interior wall thereof, adjacent the crest, said section being in spaced relation to the sides of the corrugation at the mouth of the latter and said element having another section secured to the metal panel.

4. A fabricated member for a car superstructure comprising: a sheet metal panel having a corrugation therein; a strip bridging the mouth of the corrugation and secured to the panel sheet at intervals along opposite sides of the corrugation; and a strut-like reinforcing element having a section perpendicular to the plane of the bridging strip and extending from said bridging strip to the crest zone of the corrugation, said element having another section secured to the panel at one side of the base of the corrugation.

5. In a car superstructure member, the combination with a sheet metal panel having a corrugation therein; of a strip bridging the mouth of the corrugation and secured to the panel at intervals on opposite sides of the corrugation; and a strut-like metal reinforcing element extending between said bridging strip and the crest zone of the corrugation and engaging with both said bridging strip and crest zone of the corrugation, said element being in spaced relation with respect to the side portions of the corrugation adjacent the mouth of the latter.

In witness that I claim the foregoing I have hereunto subscribed my name this 11th day of March, 1926.

ALLAN S. BARROWS.
